UNITED STATES PATENT OFFICE.

REINHARD KLINGELHÖFFER, OF WERDEN-ON-THE-RUHR, GERMANY, ASSIGNOR TO
FRIED. KRUPP AKTIENGESELLSCHAFT, OF ESSEN-ON-THE-RUHR, GERMANY.

WATER COOLER FOR LOCOMOTIVES.

Application filed December 29, 1921. Serial No. 525,648.

To all whom it may concern:

Be it known that I, REINHARD KLINGELHÖFFER, residing at Werden-on-the-Ruhr, Germany, a citizen of the German Republic, have invented a certain new and useful Improvement in Water Coolers for Locomotives, of which the following is a specification.

This invention relates to steam locomotives with a condenser and a reflux cooler composed of separate cooling cells and fitted with a blower delivering the required cooling air into said cells. The object of the invention is to enable the requisite cooling of the hot water flowing out of the condenser of the locomotive to be performed with a minimum expenditure of power.

One form of the invention is illustrated in the accompanying drawing, by way of example, in which:

Fig. 1 is a longitudinal section through the reflux cooler located on the tender,

Fig. 2 is a horizontal section taken on the line 2—2 of Fig. 1, and

Fig. 3 is a section taken on line 3—3 of Fig. 2.

In order to attain the object of the invention, it is necessary:

First, to make the entire surface area of the cooling cells as large as possible, and,

Second, to have the cross-sectional flow area of the blower large and the peripheral velocity of the blower wheel low.

Accordingly the cooling cells are arranged in a plurality of stacks and the blower is placed in the middle between the cells.

The reflux cooler is separated into separate cooling cells by means of substantially horizontal walls *m* and vertical walls *K*.

The individual cooling cells are provided in the usual manner with a perforated bottom *b'* and partly filled with a suitable filling material which presents a large surface but slight resistance to the water flow. A tube *a* is in connection with the condenser of the locomotive from which horizontal branches *a'* lead into each of the cells *b*.

Inside the cells small bore tubes *a''* are connected to the branches *a'*. The purpose of the tubes *a''* is to spray the water to be cooled over the stuffing mass.

In the center of the reflux cooler on either side of its central longitudinal plane a chamber *c* is provided in the center of which

a mechanically (for example, electrically) driven blower is situated. In the drawing the blades of the blower are designated as *e* and the air-directing means as *f*. Air is supplied to the blower by means of the canal *p* which is arranged co-axially with the blower. Each cooling cell communicates with the chamber *c* by means of an aperture *g* which is adapted to be partially closed by a shutter *h* which may be adjustably mounted as suggested in Fig. 1 (see righthand end cell second from the top). The chamber *c* is narrowed at both ends in such a manner that air from the blower *e*—*f* is supplied to all of the apertures *g* with approximate uniformity. The reflux cooler is surrounded by a shell *R* which has at its top an opening *r'* for the discharge of the cooling air. The cells *b* with the exception of the lowest, are so arranged longitudinally of the reflux cooler, that on each side a space *n* exists between the shell and the cells. The width of these spaces increases towards the opening *r'* in such a manner that the effect of the incoming cooling air is approximately uniform in all parts of said spaces. A chamber *d* communicates with the interior of the shell *R* by means of an opening *r''*, and a pipe *s* (Fig. 1) leads from chamber *d* to the condenser.

The operation is as follows:

The hot water coming from the condenser through the pipe *a*, Fig. 1, is conducted through the system of pipes *a'* *a''* to the separate cooling cells *b* and trickles down through the filling material and the bottoms *b'* upon the partitions *m*, from which it flows into the space *c* and is discharged through the opening *r''* into the receptacle *d*, Fig. 1, under the space *c*, from which it is returned by means of the pipe *s* to the condenser.

The necessary air for cooling the water is drawn in through the conduit *p* by the blower *e* *f* and forced into the cells *b* through the slots *g*. The air flows through the filling material of the separate cells *b* upwardly and arrives finally, through the exhaust passages *n*, Fig. 3, at the outlet opening *r'*. The cells *b* are therefore arranged in parallel with respect to the cooling air and to the cooling water. In its path through the openings *n*, the air, saturated with steam and drops of water, must frequently change its direction, so that the water is deposited on

the walls and flows back, whereby loss of water is avoided.

Claims:

1. A reflux cooler for locomotives provided with a condenser, said cooler being formed with a plurality of sections, vertically disposed walls forming said sections, said sections being divided into separate cooling cells, and approximately horizontal partitions forming said separate cooling cells.
2. A reflux cooler for locomotives provided with a condenser, said cooler being formed with a plurality of sections, vertically disposed walls forming said sections and approximately horizontal partitions dividing said sections into separate cooling cells, means for conducting cooling air and water to be cooled into said cells, said cells being arranged in parallel for the cooling air and for the water to be cooled.
3. A reflux cooler for locomotives provided with a condenser, said cooler being provided with a plurality of sections, a plurality of separate cooling cells contained in said sections, said sections being formed with a space therebetween and a blower disposed in the space between these of said sections which are farthest apart from each other.
4. A reflux cooler for locomotives provided with a condenser, said cooler being formed with a plurality of sections, a plurality of separate cooling cells contained in said sections, said sections being formed with a space therebetween, a blower disposed centrally of said space, said space communicating with said cooling cells, the cross-section of said space decreasing from said blower toward said cells so that the velocity of the blast of air is substantially equal at every cross-section.
5. A reflux cooler for locomotives provided with a condenser, said cooler being formed with a plurality of sections and separate cooling cells, said sections being disposed so as to provide a space therebetween, a blower disposed centrally of said space, said space communicating with said

cooling cells, said cells being provided with inlet openings communicating with said space, adjustable closure elements associated with said openings, the cross-section of said space decreasing from said blower toward said cells so that the velocity of the blast of air is substantially equal at every cross-section.

6. A reflux cooler for locomotives provided with a condenser, said cooler having a plurality of sections, each section containing a plurality of separate cooling cells, a blower disposed centrally of said sections and furnishing air to said cooling cells, outlet passages disposed on the outer side of said sections and communicating with said cells, said outlet passages having a tortuous course whereby water carried by the air passing through said passages will be separated therefrom.

7. A reflux cooler for locomotives provided with a condenser, said cooler having a plurality of sections, each section containing a plurality of separate cooling cells, a blower disposed centrally of said sections and furnishing air to said cooling cells, outlet passages disposed on the outer side of said sections and communicating with said cells, said outlet passages having a tortuous course whereby water carried by the air passing through said passages will be separated therefrom, the cross-section of said passages increasing toward the outlet opening thereof so that the velocity of the air is substantially equal at every cross-section.

8. A reflux cooler for locomotives provided with a condenser, said cooler having a plurality of sections, each section containing a plurality of separate cooling cells, said sections being disposed so as to provide a central space therebetween, a blower disposed in said space and air inlet passages for said blower disposed concentric with the shaft of the blower.

The foregoing specification signed at Essen, Germany, this 28th day of November, 1921.

REINHARD KLINGELHÖFFER.
